UNITED STATES PATENT OFFICE.

WILLIAM HINSEN, OF CAT SPRING, TEXAS.

ELEVATED RAILWAY.

1,149,764.

Specification of Letters Patent. Patented Aug. 10, 1915.

Application filed June 1, 1914. Serial No. 842,088.

To all whom it may concern:

Be it known that I, WILLIAM HINSEN, a citizen of the United States, residing at Cat Spring, in the county of Austin and State 5 of Texas, have invented certain new and useful Improvements in Elevated Railways, of which the following is a specification.

This invention relates to improvements in elevated railways and more particularly to 10 terminals and approaches to the same or approaches to stations along the line.

With the foregoing and other objects in view the invention consists in the combination and arrangement of parts to be herein- 15 after fully described in the following specification, pointed out in the claim and illustrated in the accompanying drawings which form a part of said specification and in which—

20 Figure 1 is an end elevation of my improved elevated road showing the lift or elevator associated therewith. Fig. 2 is a side elevation of the same. Fig. 3 is a section taken on line 3—3 of Fig. 4. Fig. 4 is a 25 front elevation of one of the approaches to a station or terminal. Fig. 5 is a front view of one of the supporting wheels by which the railway cars are carried. Fig. 6 is a side view of Fig. 5 taken on line 6—6 of that 30 figure.

Like reference characters indicate corresponding parts throughout the several views.

My elevated railway comprises a plurality of towers 1 disposed upon concrete or 35 similar bases 2 and certain towers throughout the line are provided with vertical guides 3 in which an elevator 4 is disposed that is raised and lowered by means of a motor 5 and cables 6 to communicate with 40 a passenger platform 7 from which access to the railway carriages 8 may be had. Each tower supports transverse girders 9 that carry depending angular supports 10 the free terminations of which are grooved lon- 45 gitudinal and carry ball and socket-sup- 50 ports 11, 12 that support the grooved spans 13 in which the cables 14 are carried upon which the grooved wheels 15 run that are connected by axles 16 that carry the car supports 17 for the railway carriages 8. The

sockets 12 are formed with bases adapted to snugly occupy the grooved portions of the supports 10 and said sockets are formed with bulged lateral portions forming oppositely disposed shoulders which serve as 55 abutments and positive supports for the spans when in inclined position thereby insuring a smooth and even movement of the car over the cables. Each car 8 is provided with suitable propelling mechanism, with 60 which my invention has nothing to do, and with all conveniences for passengers or for freight as desired.

Spans 13 supported as previously de- 65 scribed are provided directly opposite each tower 1 and the ball and socket feature of the same enables railway carriages to pass over said supports without jar or jolt, the span inclining toward the railway carriage as it approaches and again in the direction 70 of the carriage as it leaves the span, preventing any sagging of the cable-track at or adjacent the span and any perceptible vibration as the car wheels run over the portion of the cable directly supported by the 75 span.

What is claimed is:—

An elevated railway comprising a plurality of towers and transversely extending girders supported thereby, angular depend- 80 ing supports carried by said girders and formed in their free extremities with longitudinally extending grooves, sockets having a base portion adapted to fit snugly in the grooved portions of said supports and with 85 bulged lateral portions forming oppositely disposed shoulders, and grooved spans formed with integral depending balls mov- ably disposed in the said sockets whereby said spans are supported for movement in a 90 vertical plane, said movement being limited by contact of said spans with said shoulders.

In testimony that I claim the foregoing as my own I have hereto affixed my signature in the presence of two subscribing wit- 95 nesses.

WILLIAM HINSEN.
